CONTROL SYSTEM

Filed Aug. 14, 1930

2 Sheets-Sheet 2

The diagram illustrates a complex electrical circuit, likely a relay control system, with the following components and connections:

- Power Source:** A battery symbol at the bottom left provides power to the circuit.
- Relays and Contactors:** Several relays and contactors are represented by circles with internal contacts. Key components include:
  - Relay 1: Located at the top left, with coil 15b and contacts 15a, 15b, 15c, 18a, 18b, 18c, 22, and 26.
  - Relay 2: Located in the center, with coil 10a and contacts 10a, 10b, 10c, 13b, 13c, 13d, 13d', 13e, 13e', 13f, 13f', 13g, 13g', 13h, 13h', 13i, 13i', 13j, 13j', 13k, 13k', 13l, 13l', 13m, 13m', 13n, 13n', 13o, 13o', 13p, 13p', 13q, 13q', 13r, 13r', 13s, 13s', 13t, 13t', 13u, 13u', 13v, 13v', 13w, 13w', 13x, 13x', 13y, 13y', 13z, 13z', 13aa, 13ab, 13ac, 13ad, 13ae, 13af, 13ag, 13ah, 13ai, 13aj, 13ak, 13al, 13am, 13an, 13ao, 13ap, 13aq, 13ar, 13as, 13at, 13au, 13av, 13aw, 13ax, 13ay, 13az, 13ba, 13ca, 13da, 13ea, 13fa, 13ga, 13ha, 13ia, 13ja, 13ka, 13la, 13ma, 13na, 13oa, 13pa, 13qa, 13ra, 13sa, 13ta, 13ua, 13va, 13wa, 13xa, 13ya, 13za.
  - Relay 3: Located at the top right, with coil 16a and contacts 16a, 16b, 16c, 16d, 16e, 16f, 16g, 16h, 16i, 16j, 16k, 16l, 16m, 16n, 16o, 16p, 16q, 16r, 16s, 16t, 16u, 16v, 16w, 16x, 16y, 16z.
  - Relay 4: Located at the bottom right, with coil 19b and contacts 19b, 19c, 19d, 19e, 19f, 19g, 19h, 19i, 19j, 19k, 19l, 19m, 19n, 19o, 19p, 19q, 19r, 19s, 19t, 19u, 19v, 19w, 19x, 19y, 19z.
  - Relay 5: Located at the bottom center, with coil 12b and contacts 12b, 12c, 12d, 12e, 12f, 12g, 12h, 12i, 12j, 12k, 12l, 12m, 12n, 12o, 12p, 12q, 12r, 12s, 12t, 12u, 12v, 12w, 12x, 12y, 12z.
  - Relay 6: Located at the bottom left, with coil 14 and contacts 14, 15a, 15b, 15c, 18a, 18b, 18c, 22, and 26.
- Switches and Contacts:** Various switches and contacts are used throughout the circuit, including 21, 23, 24, 25, 26, 27, 28, 29, and 30.
- Wires and Terminals:** The circuit is interconnected via numerous wires and terminals, including 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 6630, 6631, 6632, 6633, 6634, 6635, 6636, 6637, 6638, 6639, 66310, 66311, 66312, 66313, 66314, 66315, 66316, 66317, 66318, 66319, 66320, 66321, 66322, 66323, 66324, 66325, 66326, 66327, 66328, 66329, 66330, 66331, 66332, 66333, 66334, 66335, 66336, 66337, 66338, 66339, 663310, 663311, 663312, 663313, 663314, 663315, 663316, 663317, 663318, 663319, 663320, 663321, 663322, 663323, 663324, 663325, 663326, 663327, 663328, 663329, 663330, 663331, 663332, 663333, 663334, 663335, 663336, 663337, 663338, 663339, 6633310, 6633311, 6633312, 6633313, 6633314, 6633315, 6633316, 6633317, 6633318, 6633319, 6633320, 6633321, 6633322, 6633323, 6633324, 6633325, 6633326, 6633327, 6633328, 6633329, 6633330, 6633331, 6633332, 6633333, 6633334, 6633335, 6633336, 6633337, 6633338, 6633339, 66333310, 66333311, 66333312, 66333313, 66333314, 66333315, 66333316, 66333317, 66333318, 66333319, 66333320, 66333321, 66333322, 66333323, 66333324, 66333325, 66333326, 66333327, 66333328, 66333329, 66333330, 66333331, 66333332, 66333333, 66333334, 66333335, 66333336, 66333337, 66333338, 66333339, 663333310, 663333311, 663333312, 663333313, 663333314, 663333315, 663333316, 663333317, 663333318, 663333319, 663333320, 663333321, 663333322, 663333323, 663333324, 663333325, 663333326, 663333327, 663333328, 663333329, 663333330, 663333331, 663333332, 663333333, 663333334, 663333335, 663333336, 663333337, 663333338, 663333339, 6633333310, 6633333311, 6633333312, 6633333313, 6633333314, 6633333315, 6633333316, 6633333317, 6633333318, 6633333319, 6633333320, 6633333321, 6633333322, 6633333323, 6633333324, 6633333325, 6633333326, 6633333327, 6633333328, 6633333329, 6633333330, 6633333331, 6633333332, 6633333333, 6633333334, 6633333335, 6633333336, 6633333337, 6633333338, 6633333339, 66333333310, 66333333311, 66333333312, 66333333313, 66333333314, 66333333315, 66333333316, 66333333317, 66333333318, 66333333319, 66333333320, 66333333321, 66333333322, 66333333323, 66333333324, 66333333325, 66333333326, 66333333327, 66333333328, 66333333329, 66333333330, 66333333331, 66333333332, 66333333333, UNITED STATES PATENT OFFICE

ROBERT E. ELLIS, OF PITTSBURGH, PENNSYLVANIA, ASSIGNEE TO UNITED ENGINEERING AND FOUNDRY COMPANY, OF PITTSBURGH, PENNSYLVANIA, A CORPORATION OF PENNSYLVANIA

CONTROL SYSTEM

Application filed August 14, 1931. Serial No. 475,221.

This invention pertains to a control system for controlling the speed of one motor in accordance with the torque developed by it and that of another in accordance to the speed of the former. More particularly, however, it relates to a system adapted for controlling the operations of the motors employed for operating the winding and unwinding reels of a metal strip mill of the type in which the strip is fed back and forth through the roll pass by such reels.

In certain mills of this type for the production of superior quality strip it is required that the reels, by means of which the strip is passed back and forth through the rolls, be driven in such a manner as to maintain the tension in the strip between the winding reel and the mill, and the back tension between the mill and the unwinding reel, at a predetermined constant value at all times.

To accomplish this it is necessary to maintain the torque on both motors constant, which, due to the continual varying of the diameter of the reels as the stock is wound up and paid out by them, necessitates that the speed of the two motors employed to operate the reels be varied continually and inversely to one another. Furthermore, the motor coupled to the unwinding reel must be caused to function somewhat as a brake in order to produce a back tension in the strip. For this reason it must be excited to run below the linear speed of the strip, and hence be driven by the strip as a generator.

With the solution of such problems in view, it is the primary object of this invention to provide an improved motor control system whereby the speed of a pair of work motors may be automatically varied inversely to one another, and the torque developed by the two maintained constant at all times.

Another object is to provide for automatically varying the speed of one motor in accordance with the torque developed by it and

that of a second motor in inverse proportions to that of the first.

A more particular object is to provide for varying the speed of the motors employed for actuating the winding and unwinding reels of a rolling mill of the above described character in such a manner as to automatically maintain the tension in the strip being passed through the mill at a predetermined value and the peripheral speed of the reels substantially constant at all times, independently of the variations in diameters of the rolls of strip on the reels.

Another object is to provide for reversing the operations of the motors employed for operating the reels of such a mill, in such a way that both reels may be rendered operative as either winding or payout reels, and the strip mounted upon them thereby subjected to the same working conditions as it is passed back and forth through the mill.

In the accompanying drawings the invention is illustrated in connection with a strip mill of the type referred to, Fig. 1 being a schematic illustration of such a mill showing it in combination with a full line wiring diagram of a control system constituting a single embodiment of the invention; and Fig. 2 a straight line wiring diagram of the same control system.

Strip mills of this general type, as illustrated in Fig. 1 of the drawings, consist chiefly of a roll pass comprising a pair of relatively small working rolls 1 arranged in a suitable frame 2 and laterally supported by a pair or more of larger diameter backing-up rolls 3, and a pair of winding and unwinding reels 5 and 6 arranged in the front and back of the roll pass for passing the strip, such as strip 4, through the mill. To simplify the handling of the strip the reels are adapted for operation in either direction so that it may be readily passed back and forth through the mill a plurality of times without removing it from the mill or reels. For operating the

reels a pair of motors 7 and 8 suitably coupled to them by a pair of shafts 9 and 11 respectively, are employed.

In the embodiment of the invention shown in the drawings motors 7 and 8 of similar size and construction and of the reversible direct current type, are provided to accommodate the demands of the reels and for operating them a source of direct current power is provided by a pair of line conductors L_1 and L_2 .

For controlling the operation of whichever of the motors 7 and 8 is selected to drive its associated reel as a winding reel, a current tension regulator 12 is employed. This regulator consists chiefly of an actuating coil 12a, which is connected in the armature circuit of the motor being controlled by it, a resistor 12b, which is connected in the field circuit, and a resistor short circuiting vibrator 12c, which is adapted to function in a well known manner in response to the current condition of the coil to vary the effect of the resistor in the field circuit and thereby vary the speed of the motor to which it is connected in accordance with the load or torque on the motor.

To provide for utilizing the one regulator for controlling both motors, its actuating coil 12a is connected in a circuit extending from conductor L_1 through a pair of contact members 13a and 13b of a multiple pole multiple throw switch 13, an automatic starting device 14, and an interlock 15b of a starting relay 15, to line conductor L_2 . The switch 13, as will appear more clearly hereinafter, is employed for reversing the operations of the two motors, and the relay 15 for establishing the various actuating circuits when the mill is set in operation.

Associated with contact members 13a and 13b on one side of switch 13 are a pair of cooperating contact elements 13a' and 13b' to which the armature 7a of motor 7 is connected. On the opposite side of the switch 13 to these elements another pair of contact elements 13a'' and 13b'' are arranged and to them the armature 8a of the motor 8 is connected. Through the agency of these contact members and elements, when switch 13 is thrown in one direction the armature of one motor is connected to the source of supply through coil 12a of the regulator, and when thrown in the other direction the armature of the other motor is so connected. By reason of such arrangement coil 12a is rendered responsive to the armature current of whichever of the motors is connected to the source of current supply and when connected in such manner the motors are adapted to drive their associated reels as strips winding mechanisms.

In a circuit similar to that in which the coil 12a is connected, the resistor 12b of the regulator is connected, the circuit extending from line conductor L_1 through an interlock 15h of relay 15, vibrator 12c and the

resistor 12b, and a pair of contact members 13c and 13d of switch 13, to line conductor L_2 . Associated with the contact elements 13c and 13d and on opposite sides of the switch are two sets of cooperating contact elements 13c' and 13d' and 13c'' and 13d'' to which the field windings 7b and 8b respectively of the motors 7 and 8 are connected. The arrangement of these connections are such that when the switch 13 is thrown to connect coil 12a in the armature circuit of one of the motors it also connects the resistor 12b in the field circuit of the same motor.

As shown in Fig. 2 of the drawings, when switch 13 is thrown to its upper position, the current regulator is connected in the field and armature circuits of motor 7, and when thrown to its lower position, in the field and armature circuits of motor 8. Hence, when switch 13 is thrown to connect either one of the motors to operate as a winding reel motor, the regulator coil 12a is excited in accordance with the current passing through its armature, which is proportional to the torque developed thereby, or, in other words, the tension in the strip being wound on the reel actuated by it. Consequently, as the tension in the strip tends to vary, coil 12a causes vibrator 12c to operate, and in a manner to either increase or decrease the effect of the resistor 12b in the field circuit of the motor, whereby the speed of the motor is so varied that the torque developed by it is maintained constant.

For supplying current to the motor utilized to actuate the reel employed as an unwinding reel when the other motor is connected to conductors L_1 and L_2 to operate its associated reel as a winding reel, a motor generator set consisting of a motor 16 and a generator 17 is employed. The motor of this set is so designed that its speed varies inversely as the strength of its field, and the generator is so designed that it produces a voltage which varies directly as its speed, which is the same as that of the motor.

To operate the motor 16 its armature 16a is connected in a circuit extending from line conductor L_1 through an interlock 15c of relay 15, the armature itself to line conductor L_2 , and its field windings 16b are adapted by means of a relay 10 to be excited when the mill is first started by current received from line conductors L_1 and L_2 , and after the mill has been brought up to a predetermined speed to one or the other of a pair of pilot generators 18 and 19 coupled by means of shafts 18c and 19c respectively to the motors 7 and 8, the one to which the windings are connected being the one coupled to the motor which is excited to operate its associated reel as a winding reel.

For starting, a circuit is provided for windings 16b, the circuit extending from line conductor L_1 through a variable resistor 21 by

means of which the excitation of the motor may be manually controlled, through interlock 15d of relay 15, back contact member 10b of relay 10, windings 16b, and back contact member 10c of relay 10 to line conductor L₂. The actuating coil 10a of relay 10 is connected by means of conductors 10x and 10y to the contact members 13a and 13b of switch 13, whereby such coil is rendered responsive to the counterelectromotive force of whichever of the motors 7 and 8 is connected to the line conductors L₁ and L₂, and the coil is so designed that it will not lift the back contact members 10b and 10c from their seat until the counterelectromotive force in the motor to which the coil is responsive is built up to a value corresponding to a preselected operating speed of the motor. The reason for providing for impressing the line voltage upon the windings 16b when the mill is first started, is that at such time there is no voltage produced by the pilot generators 18 or 19, and if no field or insufficient field is impressed upon motor 16 it will tend to run away. If such were permitted, generator 17 would also run at an excessively high rate of speed and cause the unwinding reel motor connected to it, as will presently appear, to also run at an excessive speed, the result of which would probably be that the strip would get tangled up between the unwinding reel and the mill, or at least no tension would be produced in the strip between such points.

After the mill is brought up to speed and coil 10a of relay 10 is sufficiently excited to lift its contact members, the circuit extending from line conductors L₁ and L₂ through the windings 16b is opened and the winding connected through interlocks 10d and 10e to a pair of contact members 13e and 13f of switch 13. Associated with these contact members on opposite sides of switch 13 are two sets of contact elements 13e' and 13f' and 13e'' and 13f'', to which armature 19a of pilot generator 19 and armature 18a of generator 18 are connected; variable resistors 22 and 23, respectively, being connected in series with these armatures for manually varying their output to assist in adjusting the system for operation. As will be appreciated from the foregoing, when the switch 13 is thrown to its upper position as viewed in Fig. 2 of the drawings, the armature of the pilot generator 18 is connected to the field windings 16b of motor 16, and when thrown to its lower position the armature of generator 19 is connected to such windings. Since these generators are driven by motors 7 and 8 and the motor 16 is so designed that it varies in speed inversely to the strength of its field, the motor generator set is caused to vary in speed inversely to the speed of whichever motor is connected to operate as a winding reel motor. Furthermore, as its speed determines its output the voltage produced by generator 17

varies inversely to the speed of the winding reel.

For operating motors 7 and 8 as unwinding reel motors, armature 17a of generator 17 is connected through a starting device 24 to a pair of contact members 13g and 13h of switch 13. Associated with these contact members, and on opposite sides of the switch 13, are two sets of contact elements 13g' and 13h' and 13g'' and 13h''. To the contact elements 13g' and 13h' the armature 8a of the motor 8 is connected, and to the contact elements 13g'' and 13h'' the armature 7a of the motor 7 is connected. By reason of these connections, when the switch 13 is thrown to its upper position and the motor 7a thereby connected to the source of supply or to line conductors L₁ and L₂, the armature 8a of the motor 8 is connected to the armature 17a of the generator 17 whereby motor 8 is caused to rotate at a speed varying in proportion to that of the current produced by generator 17, which, as has been explained hereinbefore, is varied inversely as the speed of motor 7. Consequently, the unwinding reel 6 will be caused to vary in an inverse ratio to that of the winding reel 5, and hence the peripheral speed of the two thereby maintained the same, which is desired.

To provide a field for motors 7 and 8 when they are connected to operate their associated reels as unwinding reels, their field windings are connected to oppositely disposed sets of contact elements 13i'' and 13j'' and 13i' and 13j', respectively, on switch 13. Interposed in cooperative relation between these sets of contact elements are a pair of contact members 13i and 13j, which are in turn connected with the line conductors L₁ and L₂. In series with these contact members there is provided a variable resistor 25 for manually varying the speed of the unwinding reel motor, so that it can be set to normally operate the reel at a sufficiently lower peripheral speed than the linear speed of the strip to produce the desired back tension.

To provide excitation for the pilot generators 18 and 19, field windings 18b are connected in a circuit extending from line conductor L₁ through a variable resistor 26, the field windings 18b and an interlock 15e of relay 15, to line conductor L₂, and field windings 19b in a circuit extending from line conductor L₁ through a variable resistor 27, the field windings 19b and an interlock 15f of relay 15 to line conductor L₂. The variable resistors are provided to assist in adjusting the system for operation.

For exciting the field windings 17b of generator 17 a circuit is provided which extends from line conductor L₁ through variable resistor 28, the field windings 17b, and interlock 15g to line conductor L₂.

As stated hereinbefore, relay 15 is employed as a starting relay, and is equipped

with an actuating coil 15a which is connected in a circuit extending from line conductor L₁ through a manually operable start and stop switch 29 and the coil 15a to line conductor L₂. When the switch 29 is closed coil 15a is energized and the relay actuated, closing all of its interlocks and the circuits controlled thereby, and when opened, coil 15a is deenergized, permitting the interlocks to fall open.

Before starting the mill in operation, line conductors L₁ and L₂ are energized through the closure of a line switch 31. The switch 13 is then operated to either its upper or lower position, depending upon the direction in which it is desired to pass the strip through the mill. With the closure of the switch 13 the reel motors are ready for operation. Thereafter, switch 29 is closed, closing relay 15 and setting the system in operation.

With the closure of relay 15, assuming that switch 13 is thrown to its upper position, motor 7 will be connected to the line conductors L₁ and L₂ through the circuits hereinbefore traced, and motor 8 to the armature of the generator 17. At the instance of starting through the operation of the starting devices 14 and 24 the motors will be gradually brought up to speed. As motor 7 approaches normal operating speed, relay 10 operates, shifting the excitation of the field windings 16b of the motor 16 from line conductors L₁ and L₂ to the armature 18c of pilot generator 18. Thereafter the motor generator is caused to function at a speed which varies inversely to that of motor 7 which is controlled by regulator 12. Due to this the output of the generator is varied inversely as the speed of motor 7, and consequently the speed of motor 8 is also varied inversely as that of motor 7. From this it follows that the speed of the unwinding reel is varied inversely to the speed of the winding reel 5. Hence as the diameter of the winding reel increases tending to increase the linear speed of the strip and thereby the tension in it, the speed of the winding reel motor is decreased, and that of the unwinding reel increased, maintaining the peripheral speeds of the two reels substantially constant as well as the tension in the strip.

After the strip has been passed through the mill in the direction referred to, starting switch 29 is opened allowing relay 15 to fall open and deenergize the operating circuits controlled by its interlocks. To return the strip through the mill in the opposite direction, switch 13 is thrown to its lower operative position and the mill is then ready for operation in the reverse direction. Thereafter with the reclosing of switch 29 the strip will be passed back through the mill in the same manner and under the same operating conditions that it was originally passed through the

mill. Such operations may be repeated as many times as is desired in the working of strip.

As will be readily appreciated by those skilled in the art, although switch 13 is illustrated and described here as a manually operable reversing switch, it may be replaced by an automatic switch which may be rendered responsive to the travel of the strip and the reversing of the mill thereby effected automatically.

According to the provisions of the patent statutes, I have explained the principle and operation of my invention, and have illustrated and described what I now consider to be its best embodiment. However, I desire to have it understood that, within the scope of the appended claims, the invention may be practiced otherwise than as specifically illustrated and described.

I claim:

1. In a control system, an electric work motor, means for automatically varying the speed of said motor in accordance with the torque developed by it, a second motor, and means responsive to the speed of the first motor for varying the speed of the second motor in inverse proportions to that of the first.

2. In a control system, a pair of electric motors, means for automatically varying the speed of one of said motors in accordance with the torque developed by it, means responsive to the speed of said motor for varying the speed of the other in inverse proportion to that of the first, and means for reversing the operation of the two.

3. The combination with a pair of reels having a pair of electric motors coupled thereto for passing strip through a rolling mill, a source of current supply, means for connecting one of said motors to operate its associated reel as a winding reel, means for connecting the other motor to operate its associated reel as an unwinding reel, means for automatically reducing the speed of the winding reel motor in accordance with the tension of the strip, and means responsive to the speed of the winding reel motor for increasing the speed of the unwinding reel motor in the same proportion that the speed of the winding reel motor is decreased.

4. The combination with a pair of reels having a pair of electric motors coupled thereto for passing strip through a rolling mill, of a source of current supply, means for connecting one of said motors to operate its associated reel as a winding reel, means for connecting the other motor to operate its associated reel as an unwinding reel, means for automatically reducing the speed of the winding reel motor in accordance with the tension of the strip, means responsive to the speed of the winding reel motor for increasing the speed of the unwinding reel motor and in the same proportion that the speed

- of the winding reel motor is decreased, and means for reversing the operation of the two motors and their control with respect to each other.
5. The combination with a pair of reels having a pair of electric motors coupled thereto for passing strip through a rolling mill, of a current type regulator connected in the operating circuits of one of said motors to control the speed thereof in accordance with the torque developed by it whereby to render the reel associated with said motor operative as a winding reel, and means responsive to the speed of said winding reel motor for inversely varying the speed of the motor coupled to the other reel to render it operative as an unwinding reel.
6. A motor control system comprising a motor having means associated therewith for automatically varying its speed in accordance with the torque developed by it, a second motor designed to vary in speed inversely as the strength of its field, and means responsive to the speed of the first motor for varying the field of the second.
7. A motor control system comprising a motor having means associated therewith for varying its speed in accordance with the torque developed by it, a second motor designed to vary in speed inversely as the strength of its field, and a pilot generator coupled to said first motor for supplying the field for the second motor.
8. The combination with a pair of reels having electric motors operatively coupled thereto for passing strip through a rolling mill, of a source of current supply, means for connecting one of said motors to said current supply, means for varying the speed of said motor in accordance with the torque developed by it, a motor generator set designed to generate a voltage varying directly as the speed of its motor, means connecting the motor of said motor generator set to said source of current supply, means responsive to the speed of the torque controlled reel motor for controlling the speed of the motor of the motor generator set, and means connecting the other of said reel motors to the generator of said motor generator set.
9. The combination with a pair of reels having electric motors operatively coupled thereto for passing strip through a rolling mill, of a source of current supply, means for connecting one of said motors to said current supply, means for varying the speed of said motor in accordance with the torque developed by it, a motor generator set designed to generate a voltage varying directly as the speed of its motor, means connecting the motor of said motor generator set to said source of current supply, means responsive to the speed of the torque controlled reel motor for controlling the speed of the motor of the motor generator set, and means connecting the other of said reel motors to the generator of said motor generator set.
10. A control system, comprising a pair of work motors, a current tension regulator adapted to vary the speed of the motor to which it is connected in a manner to maintain the torque on the motor constant, a motor generator set, means for connecting one of said work motors to said source of current in circuit relation with said regulator, a pilot generator coupled to said torque controlled motor, means for connecting said pilot generator to supply the field for the motor of said motor generator set, and means for connecting the other work motor to the generator of said motor generator set.
11. A control system, comprising a pair of work motors, a current tension regulator adapted to vary the speed of the motor to which it is connected in a manner to maintain the torque on the motor constant, a pilot generator coupled to each of said motors and adapted to generate a voltage varying directly as the speed of each motor, a motor generator set, a field winding for the motor of said set, and reversible means for connecting one of said motors to said source of current in circuit relation with said tension regulator, and for connecting the pilot generator coupled to said last-mentioned work motor to the field winding of the motor of said motor generator set and for connecting the other of said work motors to the generator of the motor generator set.
12. A control system, comprising a pair of work motors, means for manually varying the speeds of said motors, a current tension regulator adapted to vary the speed of the motor to which it is connected in a manner to maintain the torque on the motor constant, a pilot generator adapted to generate a voltage varying directly to its speed operably coupled to each of said work motors, means for manually varying the output of each of said generators, a motor generator set adapted to generate a voltage varying in direct proportion to its speed, a field winding for the motor of said set, and means for selectively connecting either of said work motors to said source of current supply through said regulator, the opposite work motor to the generator of said motor generator set and the field windings of the motor of the motor generator set to the pilot generator coupled to the motor in circuit relation with which the regulator is connected.
13. A control system comprising a pair of work motors, a current tension regulator adapted to vary the speed of the motor to

which it is connected in a manner to maintain the torque on such motor constant, a source of current supply, means for connecting one of said motors to said current supply in circuit relation with said regulator, a pilot generator operatively coupled to the motor controlled by the regulator, a field winding on said other work motor, means responsive to said regulator controlled motor for connecting said field winding to said source of current supply when the motors are first started and then automatically disconnecting it from said source of supply and to said pilot generator when the regulator controlled motor has reached a predetermined speed.

In testimony whereof I sign my name.
